UNITED STATES PATENT OFFICE.

GEORGE W. NASON, OF BRUNSWICK, MAINE.

FIRE-ALARM.

SPECIFICATION forming part of Letters Patent No. 278,586, dated May 29, 1883.

Application filed February 8, 1883. (No model.)

To all whom it may concern:

Be it known that I, GEORGE W. NASON, a citizen of the United States, residing at Brunswick, in the county of Cumberland and State of Maine, have invented a new and useful Fire-Alarm, of which the following is a specification, reference being had to the accompanying drawings.

This invention relates to fire-alarms, and has for its object to provide a simple and effective device arranged to be secured to the walls of a room or to the wall decorations, and to give an alarm when it comes in contact with fire.

15 In the drawings, Figure 1 is a perspective view of my device arranged in position on the wall. Fig. 2 is a longitudinal sectional view of the alarm. Fig. 3 is a cross-section of the same. Fig. 4 is a rear view of a picture-frame 20 to which the alarms have been applied.

Referring to the drawings, A designates a simple cylinder or tube having disks B inserted in its ends to close the same, said disks being provided with perforations C, the purpose of which will be presently described.

25 D is the fuse, which extends longitudinally through the tube A and passes through the perforations C, so that its ends E project from the end of the device. The tube is to be charged 30 with powder or some other explosive material, and after the disks are secured in position, with the fuse in place, the whole device is to be covered with an outside wrapper, F, which is preferably ornamental, and this wrapper extends around the projecting end E of the fuse, as at G, and is secured thereto by any suitable adhesive substance, or other means whereby it retains the fuse in position.

H is a strap by which the tube can be suspended in position. This strap is secured to the tube by means of a strip, I, that is provided with adhesive substance on its under surface, and is attached to the tube, with the end J of the strap between the tube and its under surface.

45 The charged tubes are to be secured in ornamental manner around the walls or cornice of the room or other place liable to fire, and they can also be arranged out of sight on articles of household furniture or decoration, such

as the picture shown in Fig. 4 of the drawings. As soon as fire touches any end of the fuse it is instantly communicated to the explosive substance inside the tube, and the latter is exploded with a loud report to alarm 55 the inmates of the house. These tubes will occasion no inconvenience at any time, and are perfectly harmless until they come in contact with fire.

I am aware that devices of this class have 60 been heretofore constructed of a shell charged with explosive material and having a fuse projecting from disks at its ends, a covering being wound around the projecting end of the fuse, and the tube being suspended as desired. 65 I therefore make no claim to this, broadly, my claim being for my own novel construction and arrangement of parts, in which a longitudinal fuse is passed loosely through the perforations in the end disks, and is secured in position and from longitudinal displacement by an outside wrapper, which is permanently pasted or otherwise secured over the tube and end disks, and is also permanently secured around the projecting ends of the fuse. The 70 parts are all thus retained in position by this general wrapper, and by reason of this arrangement and construction the device possesses superior advantages in point of simplicity and efficiency, and can be manufactured at a minimum expense. The fuse is secured merely by the permanent wrapper at its ends, which, being light, is quickly destroyed when the end of the fuse becomes ignited, when the portion of the fuse passing through 75 the disk will be readily consumed, as the fuse is not secured in the perforation in the disk, but simply passes through the same. If the fuse were secured in position by fixing it in the disk, the ignition would be slow through 80 this portion, and would in some cases be completely destroyed; but my improved manner of securing the fuse and construction entirely obviates any of these disadvantages and produces a simple and very efficient device. 85

I claim as my invention—

As an improvement in fire-alarms, the combination of the tube arranged to contain an explosive compound, the perforated disks inserted in the ends of the tube or cylinder, the 90

longitudinal fuse having its ends passing directly through the perforations in the disks at each end, and projecting from the same, but not secured therein, the outside wrapper in closing the tube and disks and secured to the same, and also projecting around the projecting ends of the fuse, and permanently pasted or otherwise secured to the same to retain it in position and from longitudinal displacement,

and the suspending-strap secured to the tube outside the said wrapper, as set forth.

In testimony that I claim the foregoing as my own I have hereto affixed my signature in presence of two witnesses.

GEORGE W. NASON.
